UNITED STATES PATENT OFFICE.

FRANK O. WOODLAND, OF WORCESTER, MASSACHUSETTS.

LABEL-AFFIXING MECHANISM.

No. 918,811.

Specification of Letters Patent. Patented April 20, 1909.

Application filed June 18, 1906. Serial No. 322,198.

To all whom it may concern:

Be it known that I, FRANK O. WOODLAND, a citizen of the United States, residing at Worcester, in the county of Worcester and 5 State of Massachusetts, have invented new and useful Improvements in Label-Affixing Mechanism, of which the following is a specification, reference being made therein to the accompanying drawings.

10 My present invention relates to the construction of wipers, more especially designed for affixing labels to the necks of bottles or similar articles, and to the combinations of the same with means for carrying and operating the wipers, and with other mechanisms that may be employed in bottle labeling machines; the object being to afford a simple, inexpensive and efficient wiping means adapted for labels that are to be laid approximately direct about the article and extending some two thirds, more or less, around the circumference thereof. Also, to provide a simple wiper construction for the purpose set forth, whereby the wipers 15 are, to a more uniform degree, rendered conformable to the curvature of the article or surface to which the labels are applied.

Another object is to provide a wiper-supporting device comprising a tipping lever and means for independently actuating said tipping lever for controlling the lateral relation of the wiper with respect to the central plane of the work or line of wiping movement, as more fully hereinafter explained.

20 I attain these objects by the mechanism illustrated in the accompanying drawings, wherein—

Figure 1 represents a front view of a wiper mechanism embodying my invention; 25 the action of the wiper devices, as when passing below the curve of the bottle neck, being indicated by dotted line on one half of the figure. Fig. 2 represents a plan view of the wiper mechanism, and Fig. 3 shows an 30 end view, top side, and section of the slotted rubber wiper-pad.

The wiper mechanism as herein shown and described, is adapted for use in labeling machines of the character described in my 35 previous application for Letters Patent, Serial No. 197,485, or machines in which the wipers effect their work by similar operation. The wiper-carrying arms have a reciprocating movement carrying the wipers past the 40 bottle or article to which the labels are to be affixed. Said arms also have lateral move-

ment, preferably by swinging upon pivoting axles, and are controlled and operated by suitable means whereby the opposite wipers are closed together during their downward movement and opened or separated while executing their upward movement. The mechanisms for thus operating the wiper-carrying arms, and for pasting and delivering labels, are not shown in the accompanying drawings, since the construction thereof is not a constituent feature of the present invention; but such mechanism may be organized for operation substantially as described in my previous application for Letters Patent above named; or in any suitable and efficient manner whereby the labels are properly presented and the wiper-carrying arms actuated with movements such as herein stated.

75 Referring to the drawings, the letter A indicates a portion of the labeling machine frame. B the bottle or article to which labels are to be affixed; F the bottle-supporting rest, at a central location in respect to the path of the wipers.

C indicates the wiper-carrying arms, which are connected with a reciprocating slide (not shown) by the shafts or pivoting axles 2, on which said arms have rocking action, controlled by suitable means for effecting the action specified.

80 The numeral 3 denotes body-label wipers, which are of approved form and secured upon suitable seats upon the wiper-carrying arms, as shown in Fig. 2.

85 As a feature of the present invention the neck-label wipers 5 are respectively supported upon the upper inwardly curved ends of tipping levers 6 that are fulcrumed, by suitable axis pivots 9, to the lower part of depending brackets or hangers C rigidly attached to the end portions of the wiper-arms C. Said hangers are provided with suitable bearing hubs or bosses 8 for supporting the pivoting 90 axles 9 which are disposed parallel with each other, and to the plane of the wiper-arms, or approximately so; and the wiper-levers 6 are arranged to swing or oscillate laterally. The wiper-levers extend above and below 95 their pivot centers, as shown; the upper curved arms of said levers being each provided with a socket or seat in or upon which the wiper proper 5 is secured by screws or other efficient means, with its working edge 100 projecting inward or toward the opposite wiper, and with a more or less degree of up-

ward inclination. The lower arms of the wiper-levers extend some distance below the fulcrum axis 9, and each lever is provided with a cam-engaging member or roller 12; 5 the lever being somewhat offset rearward, if desired, to bring the roller into alinement with stationary cam members or inclined surfaces 13 formed on a casting or piece *a* that is firmly secured to the frame A. The 10 levers 6 are provided with a retracting spring 15 for normally forcing their upper ends outward. Said springs, in the present instance, consist of contractile wire coils strained from a stud or holder on the head 15 of the lever to a stud or holder fixed on an outwardly projecting member 10 of the hanger C¹, as illustrated. A back stop 4 is provided for limiting the swing of the wiper-lever when drawn back by the spring. 20 The shape of the wiper pads may be modified to suit different shapes of labels or peculiarities of surface to which labels are in various instances affixed. An efficient form is separately shown in Fig. 3. Said wiper 25 consists of a pad 35 of rubber, or similar moderately flexible and elastic material, provided at its working end with a series of incisions or slits 7; the slits entering from the upper and under surfaces alternately 30 and extending but partially through the thickness of the pad fabric. This affords a wiping end that can readily conform itself to the swell or longitudinal curvature or to irregularities on the necks of bottles, while 35 the wiper-face is being drawn over the transverse or circumferential curvature of the bottle neck. The slits are formed by knife cuts at intervals of one fourth to one half inch apart, more or less, and all extending 40 in the direction of the wiping action. Such cuts form no appreciable opening in the pad except when the pad is strained or curved transversely to the slits; but under the latter condition they open and render 45 the pressure of the wiper more uniformly yieldable and less liable to tear some kinds of labels.

In the operation: the labels L L¹, properly glued or gummed, by suitable means there- 50 for, are presented at the positions for their affixment to the bottle, and there clamped by a suitable grip device K, as heretofore practicéd. The wiper-carrying arms C are brought into position with the wipers above 55 the labels, and then moved downward past the bottle-rest. The wipers 3 wipe-on the body-label L¹ and the wipers 5 act upon the neck-label L. At the first part of the wiping movement the levers 6 and the cams 13 con- 60 trol the wipers 5 to pass down the sides of the bottle-neck B until they approximately reach the sides where the circumference makes its upward curvature, at which time the rollers 12 on the lower members of 65 the respective levers 6 run upon the outward inclines of the cams 13, thereby causing a movement of the levers that tips inward their upper ends, carrying the wipers 5 beneath the under curved surface of the bottle-neck, (see position indicated by dotted 70 lines at the left on Fig. 1) so that the flexible end of the wiper 5 wipes-on the depending end of the neck-label below the central diameter in an efficient and ready manner. The wiping on of the body-label and the neck-label are performed simultaneously, or approximately so, at a single movement of the wiper-carrying arms C; but the controlling of the neck wipers 5 in their lateral relation to the central plane, or with respect to 75 the circumferential contour of the object wiped, is effected independently of the action of the body-label wipers and by means of the tipping wiper-levers. When the wiper-carrying arms are rocked outward for their upward return the levers 6 and wipers 5 are also rocked outward bodily therewith, and the rollers 12 pass upward at the inner sides of the cams 13 without contact; the wiper-seat ends of said levers being at such times 80 held back by the retracting springs. 85 I claim and desire to secure by Letters Patent—

1. A label-wiping mechanism, comprising a pair of vertically reciprocating laterally rockable wiper-carrying arms, a pair of tipping wiper-levers, having upwardly projecting inwardly curved wiper-supporting ends, the wipers fixed thereon, fulcrum pivots for said wiper-levers, depending pivot-supporting hangers in connection with said reciprocating wiper-carrying arms, stationary cam surfaces against which the depending ends 90 of said levers respectively contact to effect an inward movement of the wipers during 95 the latter portion of the wiping operation, and means for reciprocating the wiper-carrying arms. 100

2. In a label-affixing mechanism, the combination, with a stationary bottle-supporting rest, a pair of horizontally-disposed laterally swinging wiper-carrying arms, body-label wipers fixed thereon, and means for vertically reciprocating said wiper-carrying arms; of a pair of upright inwardly curved 115 wiper-levers having neck-label wipers fixed thereon, fulcrum-pivoting axles for said wiper-levers arranged in parallel relation and supported in bearing-brackets at the end of the wiper-carrying arms, said wiper-levers 120 arranged to swing laterally in relation to the direction of their reciprocative movement, and means that engages with and controls said wiper-levers, to effect an inward movement of the wipers relatively to the wiper-carrying arms, after the said wipers pass the outer curve of the bottle and at the latter 125 part of the wiping operation, substantially as set forth. 130

3. In a label-wiping mechanism for bottle-

- labeling machines, in combination, substantially as described, the bottle - supporting rest, horizontally disposed upwardly and downwardly reciprocating wiper - carrying arms provided with rigidly attached depending brackets having pivot-bearing hubs or bosses formed thereon; upright laterally swinging wiper-levers fulcrumed on said brackets and extending above and below their fulcrum, the fulcrum-pivoting axes disposed parallel to each other and to the wiper-carrying arms, the upper ends of said wiper-levers provided with inwardly turned wiper-seats, wipers secured upon said wiper-seats, a cam-piece disposed upon the frame at position for contact with said wiper-levers as the wiper-carrying-arms descend, and having cam-surfaces that actuate said wiper-levers to impart an inward movement to the wipers while they are passing the under curvature of the bottle, a back-stop and means for returning the wiper-levers to normal position.
4. In a label affixing mechanism, a wiper composed of a moderately flexible elastic rubber pad having its wiping end slotted by incisions or knife-cuts partially through the fabric at short intervals apart, the slits disposed longitudinally in the direction of the wiping action.
5. In a label wiping mechanism, a wiper consisting of a pad of moderately flexible elastic material, having its working edge
- provided with a series of alternately disposed slits entering at opposite faces of the pad and extending but partially through the fabric. 35
6. In a label-wiping mechanism, in combination with a bottle support, a set of body-label wipers having vertical movement, and a set of neck-label wipers having vertical 40 and lateral bodily movement while passing the position at which the wiping on of the label is effected, and means for imparting the movements thereto.
7. In a label wiping mechanism, in combination with a bottle-supporting rest, a pair of laterally rockable main wiper-carrying arms pivotally supported upon vertically reciprocating axes, a body-label wiper mounted upon each of said carrier-arms, a pair of 50 neck-label wipers, carriers therefor movably supported upon the respective main wiper-carrying arms, to afford independent lateral bodily movement of said neck-label wipers, and means for independently controlling 55 each of said neck-wiper carriers to change the lateral relation of the neck-label wipers in respect to the central vertical plane of the bottle-supporting rest.

Witness my hand this 15th day of June 60
1906.
